SMELTING FURNACE

Frank J. Zvanut, Lakewood, Clifford C. Kreager, Shaker Heights, and Charles A. Thomas, Jr., Berea, Ohio, assignors to Ferro Enamel Corporation, Cleveland, Ohio, a corporation of Ohio

Application May 17, 1946, Serial No. 670,498

8 Claims. (Cl. 49—55)

1

This invention relates to improvements in a smelting furnace particularly adapted for use in the production of frit for vitreous or porcelain enamels.

As is well known, porcelain enamel is a fused silicate composition usually applied as a coating on cast iron or steel articles to enhance their appearance and to protect the underlying metal from corrosion. In the production of such enamel proper proportions of raw materials such as feldspar, soda ash, silica, borax, fluorspar, cryolite, sodium nitrate and the like in thoroughly mixed condition are fused in a suitable smelting furnace and the resulting melt is drawn off into water. The resulting friable product so drawn off is commonly known as "frit" which, when subsequently ground or milled with water and a minor proportion of clay into liquid or thin pasty form, is termed the "slip." The slip so prepared is usually applied to the article to be coated, either by dipping the article in a bath of such slip or by spraying such slip onto the article. In either case, the resulting coating is dried and then fused by placing the article so coated in a furnace. Subsequent coatings may be deposited on the article either by a wet process or a dry process as desired, the former process having been already briefly described above and the latter process comprising sprinkling dry finely divided enamel powder onto the article while its first coat is still hot and then reinserting the article into the furnace to fuse such powder coating.

Heretofore, the smelting furnaces used in the production of frit have been of the type generally comprising a heated receptacle or hearth having a tap hole in one of its side walls adjacent the inside bottom wall thereof. When the tap hole is substantially flush with the bottom wall of the receptacle, the melt drawn off will include the sludge and impurities which settle to the bottom of the furnace. On the other hand, if the tap hole is positioned a suitable distance above the bottom wall to exclude drawing off of such sludge and impurities, then it is practically impossible to clean and scrape out the bottom of the furnace after each heat. Furthermore, a relatively large tap hole is necessary in order that the hoe-like bar generally used in clearing out such sludge can be inserted into the furnace and manipulated therein to scrape and pull such sludge toward the tap hole. Obviously, a single tap hole of circular, rectangular or other regular shape which is large enough to accommodate such a bar cannot satisfactorily be used

2

both as a tap hole and as a clean out hole, even though the clay ball plug therein is pierced with a small hole of desired size at a point near the upper extremity of such large hole well above the bottom wall of the furnace. In such case, the small pierced hole would be without lateral support and, therefore, the clay plug would quickly deform and erode when the liquid flows therewith. In addition, excessive enlargement of the small pierced hole would permit too large a stream of liquid to be drawn off into the water thereby causing excessive splattering and also improper fritting.

It is, therefore, one principal object of this invention to provide a furnace in which the aforesaid difficulties are avoided by providing a single discharge opening of form which renders such opening usable as a tap hole to exclude sludge from the melt drawn off, and in addition, usable as a clean out hole for conveniently removing the sludge from the bottom of the furnace.

It is another object of this invention to provide a furnace in which the discharge opening is shaped to effectively retain a clay ball plug therein against the head of the material within the furnace.

It is another object of this invention to provide a furnace in which the discharge opening is effectively and uniformly maintained at a temperature below that which would be detrimental to parts made of ferrous metals, whereby the separate discharge spout which contains the discharge opening can be fabricated from cast iron or cast alloy steel.

Additional objects and advantages of the invention will become apparent as the following description proceeds.

To the accompaniment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevation view of the discharge spout comprising our invention;

Fig. 2 is a horizontal cross section view of the discharge spout of Fig. 1 taken along line 2—2 of Fig. 1; and

Fig. 3 is a central vertical cross section view of the discharge spout of Fig. 1 taken along line 3—3 of Figs. 1 and 2 and showing in addition a por-

tion of the furnace to which the spout is secured.

The discharge spout shown in the drawing comprises a generally square plate-like body portion 1 which is fitted into and secured in place in an opening of corresponding cross section in one of the side walls of a furnace 2 at a region adjacent the bottom inside wall 3 thereof. Such bottom wall 3 of the furnace is preferably slightly inclined toward the aforesaid opening in the side wall. Body 1 is preferably provided with a pair of oppositely projecting lugs 4 which project beyond the extremity of the opening in the furnace and which lie adjacent the outer wall thereof and are held thereagainst by means of suitable straps or swingable links, not shown, on the furnace proper.

Centrally through the body 1 is an opening 5 of variable horizontal width as viewed in Fig. 1 and which has a section 6 of minimum width between the upper and lower extremities 7 and 8 thereof. As clearly shown in Fig. 3, the lower extremity 8 is flush with the bottom wall 3 of the furnace. In general, the contour of opening 5 approximately follows that of a vertically disposed figure eight or hour glass, as best shown in Fig. 1. The opposed side walls 9 and 10, Fig. 2, of opening 5 converge toward one another in a direction from the interior to the exterior of the furnace.

Body 1 is bored as at 11 to provide a continuous passage surrounding opening 5 and suitable threaded inlet ports 12 and threaded outlet ports 13 are in communication with passage 11 whereby cold water, for example, can be piped thereto and continuously forced through passage 11 to maintain the body 1 and also the walls of opening 5 at a temperature below that of the molten material within the furnace and also below that which would be destructive to ferrous alloys. In this way the spout can be readily cast from cast iron or alloy steel at very low cost.

Integral with body 1 is a U-shaped trough 14 which extends forwardly and downwardly from the outer face of the body. This trough serves as a conduit to either direct the melt into a water tank or the sludge into a suitable container, as the case may be.

To fully appreciate this invention, the operation of the furnace will now be briefly described. After a previous heat has been completed and the furnace has been readied for another heat a pliable clay ball is stuffed into opening 5. Such stuffing of opening 5 causes the clay ball to mushroom into engagement with the converging walls 9 and 10 of the opening to firmly resist withdrawal therefrom as by the pressure head of material within the furnace. The furnace is then loaded with the desired raw materials, as for example those previously disclosed, and is heated to effect fusing of such raw materials into a liquid form. When the melt is ready to be drawn, a tap hole 15 (shown dotted in Fig. 1) is formed in the upper portion of opening 5 as by forcing a rod through the clay ball plug. When the rod is withdrawn, the molten material from the furnace will flow through the tap hole so formed into a water tank disposed below the level of the tap hole to solidify the same and render the same friable. As indicated above, such friable product is known as frit.

As the material flows through the tap hole 15, there will, of course, be a certain amount of erosion and consequent enlargement of the tap hole, but such enlargement will not be sufficient to be detrimental to the quality of the frit pro-

duced and is not nearly as much as would be the case if there were no converging supporting walls 16 for the tap hole 15. In other words, if walls 16 were parallel and vertical or were divergent, as would be the case if opening 5 were circular and of diameter equal to the distance between the upper and lower extremities 7 and 8, the lack of support for the tap hole would permit undue erosion and deformation thereof. Because the tap hole 15 is disposed above the bottom wall 3 of the furnace, only the pure material, free of the sludge which settles to the bottom of the furnace, will be drawn off.

After having drawn off the pure material as aforesaid, a suitable container may be placed below trough 14 and then the clay ball plug can be completely removed from opening 5 to permit drainage of the sludge from the bottom of the furnace. A hoe-like bar, not shown, can then be inserted through opening 5 to pull the sludge toward opening 15 to facilitate such drainage. Because the lower extremity 8 of opening 5 is flush with the bottom wall 3 of the furnace and because the side walls 9 and 10 are flared and because the opening 5 is of considerable width across the bottom portion thereof, this hoe-like bar can be readily manipulated or moved within the furnace to thoroughly clean out all of the sludge therein and pull the same directly out through opening 5.

It is to be understood that it may not be necessary to clean out the furnace after each heat, in which case only the tap hole 15 need be plugged preparatory to running a succeeding heat.

Other modes of applying the principle of the invention may be employed, change being made as regards the details described, provided the features stated in any of the following claims or the equivalent of such be employed.

We therefore particularly point out and distinctly claim as our invention:

1. A smelting furnace comprising a receptacle having a discharge opening thru its side wall, said opening in transverse cross section having a contour approximating that of an hour glass.

2. A smelting furnace comprising a receptacle having a discharge opening through its side wall of contour approximating that of a vertically disposed hour glass.

3. A smelting furnace comprising a receptacle having a discharge opening thru its side wall of contour approximating that of a vertically disposed hour glass, the bottom of such opening being substantially flush with the bottom inside wall of said receptacle.

4. A smelting furnace comprising a receptacle having a discharge opening through its side wall formed with side walls converging toward one another from the interior to the exterior of said receptacle, said opening in transverse cross section having a contour approximating that of an hour glass.

5. In a smelting furnace, the combination of a receptacle having an opening through its side wall and a discharge spout secured in such opening, said discharge spout being formed with a discharge opening of contour approximating that of a vertically disposed hour glass.

6. In a smelting furnace, the combination of a receptacle having an opening through its side wall and a discharge spout secured in such opening, said discharge spout being formed with a discharge opening of contour approximating that of a vertically disposed hour glass, and with a

downwardly inclined trough projecting exteriorly of said receptacle.

7. In a smelting furnace, the combination of a receptacle having an opening through its side wall and a discharge spout secured in such opening, said discharge spout being formed with a discharge opening of contour approximating that of a vertically disposed hour glass, the side walls of such discharge opening being convergent toward one another from the interior to the exterior of said receptacle.

8. A discharge spout for smelting furnaces comprising a body having an opening therethrough, said opening in transverse cross section having a contour approximating that of an hour glass. 15
